TELEPHONE SYSTEM

Pier Bakker, Chicago, Ill., assignor to Associated Electric Laboratories, Inc., Chicago, Ill., a corporation of Delaware

Application April 11, 1940, Serial No. 329,088

25 Claims. (Cl. 179—18)

The present invention relates to telephone systems and, more particularly, to improvements in automatic telephone systems of the character of that disclosed and claimed in the copending application of Clarence E. Lomax and Pier Bakker, Serial No. 269,139, now U. S. Patent No. 2,214,908, granted Sept. 17, 1940, filed April 21, 1939, wherein finder switches are employed to extend connections between calling lines and associated numerical switches.

It is an object of the present invention to provide in an automatic telephone system, improved distributor apparatus for selecting idle finder switches for the use of calling lines and for controlling the operation of the selected finder switches.

Another object of the invention is to provide in an automatic telephone system, improved distributor apparatus for selectively controlling the operation of the finder switches in two associated groups of finder switches to find calling lines in two associated groups of lines.

The features of the present invention are illustrated as being incorporated in a telephone system provided with an exchange terminating first and second groups of lines and comprising first and second groups of finder-connector links, each link including a finder switch and a connector switch, and first and second distributors respectively associated with the first and second groups of links. These switches are so connected and arranged that each finder switch and each connector switch has access to each line in the system.

In accordance with one feature of the invention the telephone system comprises first and second groups of lines, first and second groups of finder switches, each of the finder switches in each of the groups of finder switches having access to each of the lines in each of the groups of lines and being operative to find a calling line accessible thereto, first blocking means normally effective positively to prevent the finder switches in the first group of finder switches from finding lines in the second group of lines, and a second blocking means normally effective positively to prevent the finder switches in the second group of finder switches from finding lines in the first group of lines. Also the system comprises a first distributor operative to assign idle ones of the finder switches in the first group of finder switches in a predetermined order and to initiate operation of an assigned one of the last-mentioned finder switches, means for arresting operation of and for rendering busy the last-men-

tioned finder switch when a line is found thereby, means governed when all of the finder switches in the first group of finder switches are rendered busy for rendering ineffective the second blocking means, a second distributor operative to assign idle ones of the finder switches in the second group of finder switches in a predetermined order and to initiate operation of an assigned one of the last-mentioned finder switches, means for arresting operation of and for rendering busy the last-mentioned finder switch when a line is found thereby, and means governed when all of the finder switches in the second group of finder switches are rendered busy for rendering ineffective the first blocking means. Finally, this system comprises means governed in response to the presence of a calling line in the first group of lines for operating the first distributor in the event there is an idle finder switch in the first group of finder switches and for operating the second distributor in the event all of the finder switches in the first group of finder switches are busy and governed in response to the presence of a calling line in the second group of lines for operating the second distributor in the event there is an idle finder switch in the second group of finder switches and for operating the first distributor in the event all of the finder switches in the second group of finder switches are busy.

30 In accordance with another feature of the invention each of the distributors is operative through a cycle to initiate operation of a preselected finder switch in the associated group of finder switches and then to arrest operation of 35 and to render busy the last-mentioned finder switch when a line is found thereby and finally to select another idle one of the finder switches in the associated group of finder switches.

In accordance with a further feature of the invention the first blocking means comprises a blocking circuit adapted to be completed to prevent the finder switches in the first group of finder switches from finding lines in the second group of lines; and the second blocking means comprises a blocking circuit adapted to be completed to prevent the finder switches in the second group of finder switches from finding lines in the first group of lines. Furthermore, the first distributor comprises means governed when a finder switch in the first group of finder switches is operating for preparing a point in the first blocking circuit and additional means governed while a finder switch in the first group of finder switches is operating or when there is an idle finder switch in the first group of finder switches for

preparing a point in the second blocking circuit; while the second distributor comprises means governed while a finder switch in the second group of finder switches is operating for preparing a point in the second blocking circuit and additional means governed while a finder switch in the second group of finder switches is operating or when there is an idle finder switch in the second group of finder switches for preparing a point in the first blocking circuit. Finally, each of the blocking circuits is completed only when points are prepared therein in both the first distributor and the second distributor.

Further features of the invention pertain to the particular arrangement of the circuit elements of the system and to the particular connection and arrangement of the elements of the distributors and the links incorporated therein, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings in which Figs. 1 and 2, taken together, illustrate a telephone system embodying the present invention.

Referring now more particularly to Figs. 1 and 2 of the drawings, the telephone system there illustrated comprises an exchange terminating a plurality of subscriber lines, including the subscriber lines 101 and 230. Also, the exchange comprises a number of finder-connector links, including the links 60 and 70, for setting up connections between the various subscriber lines. More specifically, the exchange has an ultimate capacity of 200 lines, these lines being arranged in first and second groups of 100 lines each. Each of the links comprises a 200 point finder switch having access to each line in the system and a 200 point connector switch having access to each line in the system.

Furthermore, the links are arranged in first and second groups, each group of links being provided with a distributor individual thereto for assigning idle ones of the links in the group to the use of calling ones of the lines. The number of links included in each group is determined by the amount of traffic which the exchange is required to handle and usually satisfactory service may be rendered when each of the two groups of links includes ten links.

More particularly, the first group of links includes the link 60, which comprises the finder switch 130 and the connector switch 215, and is provided with the distributor 300; while the second group of links includes the link 70, which comprises the finder switch 310 and the connector switch 311, and is provided with the distributor 312. The first and second groups of lines are respectively associated with the distributors 300 and 312; whereby calling lines in the first group of lines are normally assigned for use idle ones of the links in the first group of links, and calling lines in the second group of lines are normally assigned for use idle ones of the links in the second group of links, thereby rendering it possible to extend simultaneously a call initiated on a line in each of the two groups of lines. Furthermore, the distributors 300 and 312 are so connected and arranged that a call initiated on a line in the first group

of lines is assigned for use an idle link in the second group of links in the event all of the links in the first group of links are busy; and a call initiated on a line in the second group of lines is assigned for use an idle link in the first group of links in the event all of the links in the second group of links are busy.

A subscriber substation is associated with each of the subscriber lines, the subscriber substations 10 A and B being respectively associated with the subscriber lines 101 and 230. Each of the subscriber substations is provided with a telephone instrument, a dial mechanism and a ringer. Also, a line circuit is individually associated with each of the subscriber lines, the line circuits 100 and 240, illustrated in Fig. 1, being respectively associated with the subscriber lines 101 and 230. Preferably, these line circuits are identical, each including a line relay and a cutoff relay, these 20 relays in the line circuit 100 being respectively indicated at R120 and R110.

Preferably, each of the links is connected and arranged in a manner similar to that of the link 60 which comprises the finder switch 130 and the connector switch 215. The finder switch 130, as best shown in Fig. 1, comprises a switching mechanism 140 of the 200 point Strowger type including a bank of fixed contact sets arranged in ten vertical levels, each level including upper and lower rows of contact sets, each row of contact sets including ten circumferentially disposed contact sets, each contact set terminating a line extending thereto; and a row of fixed contacts arranged in vertical alignment.

30 Also, the Strowger mechanism 140 comprises upper and lower wiper sets respectively including the wipers 141, 142, 143 and 144, 145, 146 carried by a carriage movable in both vertical and rotary directions, the upper and lower wiper sets being respectively associated with the upper and lower rows of contact sets in the bank of fixed contact sets; and a control wiper 147 carried by the carriage, the control wiper 147 being associated with the row of fixed contacts.

40 Also, this Strowger mechanism includes a vertical magnet M170 for moving the carriage in the vertical direction, a rotary magnet M171 for moving the carriage in a rotary direction, and a release magnet M172 for releasing the carriage and for causing it to be returned to its normal position. Associated with this Strowger mechanism are two sets of switch springs S175 and S179 which are actuated by the movement of the carriage in the vertical direction away

50 from its normal position, and a set of switch springs S174 which is actuated by the movement of the carriage into its eleventh rotary position. Also, it is noted that the upper and lower wiper sets respectively terminate the trunk lines 131 and 135 included in the finder switch 130, which

60 trunk lines are operatively associated with the trunk line 115 extending between the finder switch 130 and the connector switch 215. Also, the finder switch 130 comprises a start relay R140, two switching relays R150 and R160, a supervisory lamp L128 and a manually operable busy switch S183.

70 Also, the connector switch 215, illustrated in Fig. 1, comprises a Strowger mechanism of the 200 point type having access to each line in the system, the connector switch 215 being connected and arranged in a conventional manner.

Preferably, each of the distributors is connected and arranged in a manner similar to that of the distributor 300 individually associated

with the first group of links which comprises, as best shown in Fig. 2, a rotary switch 301 including six banks of fixed contacts and six wipers individually associated therewith, the corresponding contacts in each bank terminating the control conductors extending to the respective links in the first group of links, and the wipers terminating the control conductor extending to the distributor. Also, the rotary switch 301 includes a rotary magnet M308 for driving the wipers associated with the contact banks in a rotary direction. The distributor 300 also comprises a start relay R345, a busy transfer relay R340, a step relay R370, a transfer relay R360, a timing relay R315, first and second test relays R328 and R325, respectively, and a number of control relays R350, R380, R390 and R330. Also associated with the distributor 300 are a supervisory lamp L409 and a busy switch S334.

The distributor 300 is of the preselective type in that an idle link in the first group of links is selected to be assigned to the use of a calling line in the first group of lines prior to the initiation of a call on the line therein and another idle link in the first group of links is automatically selected to be assigned to the use of the next calling line in the first group of lines as soon as the selected link operates to find a calling line in the first group of lines. Also, the distributor 300 is so connected and arranged that, when all of the links in the first group of links are busy, the start circuit of the distributor 300 is transferred to the distributor 312 associated with the second group of lines, whereby the distributor 312 assigns idle ones of the links in the second group of links to the use of calling lines in the first group of lines. Further, the distributors 300 and 312 are so connected and arranged that the finder switch of a link in the first group of links is positively prevented from finding a line in the second group of lines while the distributor 312 is operating and that the finder switch of a link in the second group of links is positively prevented from finding a line in the first group of lines while the distributor 300 is operating.

A better understanding of the connection and arrangement of the apparatus incorporated in the telephone system will be facilitated from a consideration of the operation thereof incident to the extension of a call from the subscriber substation A to the subscriber substation B. The call is first initiated at the substation A by removing the receiver of the telephone instrument thereat from its hook, thereby to complete a bridge path at the substation A between the line conductors C102 and C103 of the subscriber line 101 extending to the substation A. When this bridge path is completed between the line conductors of the subscriber line 101, a circuit is completed for energizing the winding of the line relay R120 in the line circuit 100 individually associated with the subscriber line 101, which circuit extends from ground, at RA112, by way of RA112, C102, the bridge path between the line conductors C102 and C103 of the subscriber line 101, C103, RA111, and the winding of R120 to battery. When energized over the above-traced circuit the line relay R120 operates to complete, at RA122 and RC123, an obvious path for applying ground potential to the control conductor C105 of the subscriber line 101, thereby to mark the subscriber line 101 as busy to the connector switches having access thereto. Also, the line relay R120 completes, at RA125, an

obvious path for applying ground potential to the control conductor C108, thereby to cause ground potential to be applied by way of the circuit network 191 to the start conductor C316 extending into the distributor 300, assuming that the subscriber line 101 is included in the first group of subscriber lines. Also, this application of ground potential to the control conductor C108 marks, by way of the circuit network 191 and the contacts in the rows of contacts in the Strowger mechanisms included in the finder switches, the level wherein the subscriber line 101 is terminated, the contact in the row of contacts in the Strowger mechanism 140 included in the finder switch 130 being indicated at 148. Also, upon operating, the line relay R120 completes, at RA121, a path for applying battery potential to the control conductor C104 of the subscriber line 101, thereby to mark the rotary position of the contact sets in the contact banks of the Strowger mechanisms included in the finder switches terminating the subscriber line 101. This path for applying battery potential to the control conductor C104 of the subscriber line 101 extends from battery at the winding of the cutoff relay R118, by way of the winding of R110 and RA121, to C104.

This application of ground potential to the start conductor C316 extending into the distributor 300 completes a circuit for energizing the winding of the start relay R345, this circuit extending from ground by way of RA125, the control conductor C108, a resistor included in the circuit network 191, the start conductor C316, RA341, RC343 and the winding of R345 to battery. When energized over the above-traced circuit, the start relay R345 operates to initiate operation of the distributor 300, thereby to cause the preselected idle one of the links in the first group of links to be assigned to the use of the calling subscriber line. More particularly, upon operating, the start relay R345 completes, at RA346, a circuit for energizing the winding of the control relay R350 in series with the rotary magnet M308 of the rotary switch 301, this circuit extending from ground by way of RA330, RC331, RA365, RA346, the winding of R350, RA345, MA308, and the rotary magnet M308 to battery. When the above-traced series circuit is completed, the rotary magnet M308 does not operate due to the high series resistance of the winding of the control relay R350. However, the control relay R350 does operate. Upon operating, the control relay R350 completes, at RA358, an alternative holding circuit for energizing the winding of the busy transfer relay R340, this circuit extending from ground by way of RA344, RA358 and the winding of R340 to battery. It is noted that the winding of the busy transfer relay R340 is normally energized by way of a number of multiple circuits completed in idle ones of the finder switches of the first group of links, one of these multiple circuits being completed at this time in the finder switch 130 of the link 60 and extending from ground by way of RA144, RC145, the switch springs 186 and 187 of the busy switch S183, the switch springs 178 and 177 of the set of switch springs S175, the all-trunks-busy conductor C321, the switch springs 335 and 336 of the busy switch S334, RA333, and the winding of R340 to battery. Also, it will be understood that a similar multiple circuit will be completed in each of the finder switches of idle ones of the links in the first group of links.

Also, upon operating, the control relay R350 completes, at RA356, a point in a circuit traced hereinafter for energizing the winding of the timing relay R375, prepares, at RA357, a point in a circuit traced hereinafter for energizing the lower winding of the transfer relay R360, prepares, at RA358, a point in an alternative circuit traced hereinafter for energizing the winding thereof in series with the rotary magnet M308 of the rotary switch 301, prepares, at RA353 and RC355, a point in a circuit traced hereinafter for energizing the rotary magnet M308 directly from the guard conductor C322 and prepares, at RA352, a point in a circuit traced hereinafter for energizing the vertical magnet M170 of the finder switch 130 of the link 60, assuming that the link 60 has been preselected by the distributor 300. Also, the control relay R350 completes, at RA351, a circuit traced hereinafter for energizing the winding of the start relay R140 in the finder switch 130 of the preselected link 60. As previously noted, the link 60 in the first group of links has been previously selected by the distributor 300 for the use of a calling line. Accordingly, the wipers 302 to 307, inclusive, of the rotary switch 301 engage the contacts in the associated contact banks terminating the control conductors extending to the finder switch 130 of the link 60.

The circuit for energizing the winding of the start relay R140 in the finder switch 130 extends from ground by way of RA351, the wiper 303 and associated contact of the rotary switch 301, the finder start conductor C318, and the winding of R140 to battery. When energized over the above-traced circuit, the start relay R140 operates to complete, at RA141, an obvious path between the line conductors C116 and C117 of the trunk line 115 extending between the finder switch 130 and the connector switch 215 of the link 60, and to complete, at RA144 and RC146, an obvious path for applying ground potential to the control conductor C118 of the trunk line 115. When these paths are thus completed the connector switch 215 is conditioned to be operative in response to a digit dialed thereinto, in a manner more fully explained subsequently.

Also the start relay R140 prepares at RA142, a circuit traced hereinafter for energizing the winding of the second test relay R325 in the distributor 300, interrupts at RA143 a point in a path traced hereinafter for applying ground potential to the guard conductor C322, interrupts at RA144 and RC145, a point in the previously traced path for applying ground potential in the finder switch 130 to the all-trunks-busy conductor C321, prepares at RA147, a circuit traced hereinafter for energizing the rotary magnet M171, and completes at RA148, a circuit for energizing the vertical magnet M170. The circuit for energizing the vertical magnet M170 extends from ground by way of RA352, RA371, RA361, RC362, the wiper 304 and associated contact of the rotary switch 301, the vertical conductor C320, RA148, and the vertical magnet M170 to battery. When energized over the above-traced circuit, the vertical magnet M170 operates. Upon operating, the vertical magnet M170 drives the carriage of the Strowger mechanism 140 of the finder switch 130 one step in the vertical direction and completes, at MA170, a circuit for energizing the winding of the step relay R370 in the distributor 300. The circuit for energizing the winding of the step relay R370 extends from ground by way

of MA170, the interrupter conductor C319 and the winding of R370 to battery.

When energized over the above-traced circuit, the step relay R370 operates to interrupt, at 5 RA371, a point in the previously traced circuit for energizing the vertical magnet M170, thereby to cause the vertical magnet M170 to restore. Upon restoring, the vertical magnet M170 interrupts, at MA170, the previously traced circuit for 10 energizing the winding of the step relay R370, thereby to cause the latter relay to restore. Upon restoring, the step relay R370 re-completes, at RA371, the previously traced circuit for energizing the vertical magnet M170, 15 whereupon the vertical magnet M170 operates to drive the carriage of the Strowger mechanism 140 of the finder switch 130 an additional step in the vertical direction and to recomplete, at MA170, the previously traced circuit for energizing the winding of the step relay R370 in the distributor 300.

The step relay R370 in the distributor 300 and the vertical magnet M170 in the finder switch 130 continue to interact in the above-described manner, thereby to cause the carriage of the Strowger mechanism 140 of the finder switch 130 to be driven step by step in the vertical direction until the control wiper 147 engages a contact in the row of contacts associated therewith having marking ground potential thereon. In the present instance, the carriage of the Strowger mechanism 140 of the finder switch 130 is driven two steps in the vertical direction, whereupon the control wiper 147 engages the contact 148 in the row of contacts 25 having marking ground potential thereon. A circuit is then completed for energizing the lower winding of the transfer relay R360 in series with the winding of the step relay R370, this circuit extending from the grounded contact 148 in the row of contacts by way of the control wiper 147, the first test conductor C317, the wiper 302 and associated contact of the rotary switch 301, RA366, RC367, the lower winding of R360, RA357, and the winding of R370 to battery. It 30 is noted that the above-traced circuit for energizing the lower winding of the transfer relay R360 in series with the winding of the step relay R370 is completed immediately the carriage of the Strowger mechanism 140 of the finder switch 35 130 is driven the second step in the vertical direction. Accordingly, the step relay R370 does not restore incident to the restoration of the vertical magnet M170 at this time.

Shortly after the transfer relay R360 is energized over the above-traced circuit it operates, this relay being of the slow-to-operate type. Upon operating, the transfer relay R360 completes, at RA369, a holding circuit traced hereinafter for energizing the upper winding thereof, 40 interrupts, at RA366 and RC367, the previously traced circuit for energizing the lower winding thereof in series with the winding of the step relay R370, and prepares, at RA366 and RC368, a circuit traced hereinafter for energizing the 45 winding of the first test relay R320. Also, upon operating, the transfer relay R360 interrupts, at RA365, a point in the previously traced original circuit for energizing the winding of the control relay R350 in series with the rotary magnet M308, an alternative circuit for energizing the winding of the control relay R350 in series with the rotary magnet M308 being completed at 50 this time. Also, the transfer relay R360, at RA361 and RC362, a further point in the pre-

viously traced circuit for energizing the vertical magnet M170 and prepares, at RA361 and RC364, a point in a circuit traced hereinafter for energizing the rotary magnet M171.

As previously noted, upon operating, the control relay R350 completes, at RA358, a circuit for energizing the winding of the timing relay R375, this circuit extending from ground by way of RA356, RA383, RC334, and the winding of R375 to battery. When energized over the above-traced circuit, the timing relay R375 operates to complete, at RA376 and RC378, RC379, a circuit for energizing the winding of the control relay R380, this circuit extending from ground by way of RA356, RA376, RC378, RC379, and the winding of R380 to battery. Shortly after the control relay R380 is energized by way of the above-traced circuit, this relay operates, this relay being of the slow-to-operate type. Upon operating, the control relay R380 completes, at RA386, a holding circuit for energizing the winding thereof, this circuit extending from ground by way of RA356, RA376, RC378, RA386, and the winding of R380 to battery. Also, upon operating, the control relay R380 interrupts, at RA382 and RC383, a point in a circuit traced hereinafter for energizing the upper winding of the control relay R390, and prepares, at RA382 and RC384, a holding circuit traced hereinafter for energizing the upper winding of the transfer relay R360. Also, the control relay R380 completes, at RA381, the previously mentioned alternative circuit for energizing the winding of the control relay R350 in series with the rotary magnet M308, this circuit extending from ground by way of RA381, RA359, the winding of R350, RA345, MA308, and the rotary magnet M308 to battery. Finally, upon operating, the control relay R380 completes, at RA385, an obvious circuit for energizing the upper winding of the control relay R330, thereby to cause the latter relay to operate. Upon operating, the control relay R330 completes, at RA336, a holding circuit for energizing the lower winding thereof, this circuit extending from ground by way of RA351, RA336, and the lower winding of R330 to battery. Also, the control relay R330 interrupts, at RA330 and RC331, a point in the previously traced original circuit for energizing the winding of the control relay R350 in series with the rotary magnet M308, and completes, at RA330 and RC332, an obvious multiple alternative circuit for energizing the winding of the control relay R350 in series with the rotary magnet M308. Furthermore, the control relay R330 interrupts, at RA333 and RC334, a point in the previously traced circuit for energizing the winding of the timing relay R375; prepares, at RA333 and RC335, a point in the previously mentioned holding circuit for energizing the upper winding of the transfer relay R360; prepares, at RA337, a point in a circuit traced hereinafter for energizing the winding of the first test relay R320; and prepares, at RA338, a point in a circuit traced hereinafter for energizing the winding of the second test relay R325.

When the previously traced circuit for energizing the winding of the timing relay R375 is interrupted, the latter relay restores, thereby to cause the weighted armature RA376 thereof to vibrate between the associated contacts RC377 and RC378, in order to complete intermittently the previously traced holding circuit for energizing the winding of the control relay R380. It is noted that the weighted armature RA376 vi-

brates between the contacts noted for a predetermined time interval, thereby to retain the control relay R380 in its operated position during this time interval.

5 The previously mentioned holding circuit for energizing the upper winding of the transfer relay R360 extends from ground by way of RA356, RA383, RC335, RA382, RC384, RA388, and the upper winding of R360 to battery; while the previously mentioned circuit for energizing the rotary magnet M171 extends from ground by way of RA352, RA371, RA361, RC384, RA321, RC322, RA326, RC327, the rotary conductor C324, RA165, RA157, RA147, and the rotary magnet M171 to battery. When energized over the above-traced circuit, the rotary magnet M171 operates to drive the carriage of the Strowger mechanism 140 of the finder switch 130 one step in the rotary direction and to complete, at MA171, an alternative circuit for energizing the winding of the step relay R370 in the distributor 300. The circuit for energizing the winding of the step relay R370 extends from ground by way of MA171, the interrupter conductor C319, and the winding of R370 to battery. When energized over the above-traced circuit, the step relay R370 operates to interrupt, at RA371, the previously traced circuit for energizing the rotary magnet M171, thereby to cause the rotary magnet to restore. Upon restoring, the rotary magnet M171 interrupts, at MA171, the previously traced alternative circuit for energizing the winding of the step relay R370, thereby to cause the step relay to restore and recomplete, at RA371, the previously traced circuit for energizing the rotary magnet M171.

35 The step relay R370 in the distributor 300 and the rotary magnet M171 in the finder switch 130 continue to interact in the manner described above until the carriage of the Strowger mechanism 140 of the finder switch 130 is rotated in the rotary direction to the position of the contact set terminating the calling subscriber line 101, at which time the wiper 143 of the upper wiper set engages the contact of the contact set terminating the control conductor C104 of the subscriber line 101, assuming that the line 101 is accessible to the upper wiper set of the Strowger mechanism 140 of the finder switch 130, whereupon a circuit is completed for energizing the winding of the cutoff relay R110 in the line circuit 100 in series with the first test relay R320 in the distributor 300. The last-mentioned circuit extends from ground by way of RA337, the unidirectional current conducting device or copper oxide rectifier 347, the winding of R320, RC368, RA366, the wiper 302 and associated contact of the rotary switch 301, the first test conductor C317, the wiper 143 of the upper wiper set, the associated contact terminating the control conductor C104 of the subscriber line 101, C104, RA121 and the winding of the cutoff relay R110 to battery.

65 When the cutoff relay R110 in the line circuit 100 is energized by way of the above-traced circuit, it does not operate due to the high series resistance of the first test relay R320 in the distributor 300. However, the first test relay R320 does operate. Upon operating, the first test relay R320 interrupts, at RA321 and RC322, the previously traced circuit for energizing the rotary magnet M171 and completes, at RA321 and RC323, a circuit for energizing the winding of the switching relay R160 in the finder switch 130. The circuit for energizing the winding of the switching relay R160 extends from ground by

way of RA352, RA371, RA361, RC364, RA321, RC323, the wiper 308 and associated contact of the rotary switch 301, the conductor C323, RA158, and the winding of R160 to battery. When energized over the above-traced circuit, the switching relay R160 operates to interrupt, at RA166, a further point in the previously traced circuit for energizing the rotary magnet M171 and to complete, at RA164, a holding circuit for energizing the winding thereof, this circuit extending from ground, at RA144, by way of RC148, RA164, and the winding of R160 to battery. Also, upon operating, the switching relay R160 connects the trunk line 131 terminated by the upper wiper set to the trunk line 115 extending between the finder switch 130 and the connector switch 215. Specifically, the conductors C132, C133 and C134 of the trunk line 131 are respectively connected, at RA161, RA162 and RA163, to the conductors C116, C117 and C118, respectively, of the trunk line 115. When the grounded control conductor C118 of the trunk line 115 is connected to the control conductor C134 of the trunk line 131, an alternative circuit is completed for energizing the winding of the cutoff relay R110 in the line circuit 100, this circuit extending from the grounded control conductor C118 of the trunk line 115 by way of RA163, the control conductor C134 of the trunk line 131, the wiper 143 of the upper wiper set, the associated contact terminating the control conductor C104 of the subscriber line 101, C104, RA121, and the winding of R110 to battery. When energized over the above-traced circuit, the cutoff relay R110 operates to complete, at RA113, a holding circuit for energizing the winding thereof, this circuit extending from the grounded control conductor C104 of the subscriber line 101 by way of C104, RA113, and the winding of R110 to battery. Also, upon operating, the cutoff relay R110 interrupts, at RA111 and RA112, points in the previously traced circuit for energizing the winding of the line relay R120, thereby to free the subscriber line 101 of impedance elements and to cause the line relay R120 to restore.

It is noted that, when the carriage of the Strowger mechanism of the finder switch 130 is operated away from its normal position the first step in the vertical direction, the sets of switch springs S175 and S179 are actuated. More specifically, the switch springs 181 and 182 of the set of switch springs S179 are actuated into disengagement; while the switch springs 181 and 180 of the set of switch springs S179 are actuated into engagement. When the switch springs 181 and 180 of the set of switch springs S179 are actuated into engagement, a point is prepared in a path traced hereinafter for applying ground potential to the guard conductor C322. Also, the switch springs 178 and 177 of the set of switch springs S175 are actuated into disengagement and the switch springs 178 and 176 of the set of switch springs S175 are actuated into engagement. When the switch springs 178 and 177 of the set of switch springs S175 are actuated into disengagement, a further point in the previously traced path for applying ground potential to the all-trunks-busy conductor C321 is interrupted; and when the switch springs 178 and 176 of the set of switch springs S175 are actuated into engagement, a point is prepared in a circuit traced hereinafter for illuminating the supervisory lamp L128.

Also, upon operating, the switching relay R160

in the finder switch 130 interrupts, at RA166 and RC168, a point in a circuit traced hereinafter for energizing the release magnet M172, and prepares, at RA166 and RC167, an additional point in the previously mentioned circuit for illuminating the supervisory lamp L128. Furthermore, the switching relay R160 interrupts, at RA160, a point in a circuit traced hereinafter for energizing the winding of the switching relay R150, thereby to prevent operation of the switching relay R150 at this time; and completes, at RA169, the previously mentioned path for applying ground potential to the guard conductor C322, this path extending from ground by way of the switch springs 180 and 181 of the set of switch springs S179, RA169, and the switch springs 185 and 184 of the busy switch 183 to the guard conductor C322. This application of ground potential to the guard conductor C322 completes a circuit for energizing the rotary magnet M308 of the rotary switch 301, this circuit extending from the grounded guard conductor C322 by way of the wiper 305 and associated contact of the rotary switch 301, RA353, RC355, and the winding of M308 to battery. When energized over the above-traced circuit, the rotary magnet M308 operates, thereby to condition the wipers of the rotary switch 301 to be driven one step in the rotary direction. Also, upon operating, the rotary magnet M308 interrupts, at MA308, the previously traced alternative circuit for energizing the rotary magnet M308 in series with the winding of the control relay R350, thereby to cause the control relay R350 to restore.

Upon restoring, the control relay R350 interrupts, at RA353 and RC355, the previously traced circuit for energizing the rotary magnet M308, thereby to cause the rotary magnet M308 to restore. Upon restoring, the rotary magnet M308 drives the wipers 302 to 307, inclusive, of the rotary switch 301 one step in the rotary direction and into engagement with the contacts in the associated contact banks terminating the control conductors extending to the finder switch of the next link. The subsequent operation of the distributor 300 depend upon the idle or busy condition of the finder switch of the next link, in a manner more fully described subsequently.

Assuming that there are no other calls in the first group of lines at this time, when the line relay R120 of the line circuit 100 associated with the subscriber line 101 restores it interrupts, at RA125, the previously traced path for applying ground potential to the control conductor C190, interrupts, at RA122 and RC123, the previously traced path for applying ground potential to the control conductor C105 of the subscriber line 101, and completes, at RA122 and RC124, an alternative path for applying ground potential to the control conductor C105, thereby to mark the subscriber line 101 as busy to the connector switches having access thereto. The last-mentioned path extends from the grounded control conductor C104 of the subscriber line 101 by way of RA113, RC124 and RA122, to the control conductor C105.

When ground potential is removed from the control conductor C190, the previously traced circuit for energizing the winding of the start relay R345 in the distributor 300 is interrupted, thereby to cause the start relay R345 to restore. Upon restoring, the start relay R345 interrupts, at RA346, the previously traced original circuit for energizing the winding of the control relay R350 in series with the rotary magnet M308. Also, when the control relay R350 restores, as pre-

viously noted, it interrupts, at RA359, a further point in the circuit for energizing the winding thereof in series with the rotary magnet M308. Also, at RA353 and RC354, the wiper 305 of the rotary switch 301 is connected by way of the self-interrupting contact MA308 and the rotary magnet M308 to battery, this connection extending from the wiper 305 by way of RA353, RC354, RA345, MA308, and the rotary magnet M308 to battery.

In the event the finder switch of the next link in the first group is busy at this time, ground potential appears upon the guard conductor thereof, corresponding to the guard conductor C322 of the finder switch 130, as previously noted, thereby to complete a circuit extending by way of the previously traced connection for energizing the rotary magnet M308. When thus energized, the rotary magnet M308 operates to condition the wipers of the rotary switch 301 to be driven an additional step in the rotary direction and to interrupt, at MA308, the previously traced circuit for energizing the rotary magnet M308. When the previously traced circuit for energizing the rotary magnet M308 is interrupted, the rotary magnet restores, thereby to drive the wipers of the rotary switch 301 an additional step in the rotary direction. The rotary magnet M308 continues to operate in the above-described manner in order to cause the wipers of the relay switch 301 to be driven step by step in the rotary direction until the finder switch of an idle link in the first group of links is found. When the finder switch of an idle link in the first group of links is found, further operation of the rotary magnet M308 is arrested, due to the fact that no ground potential appears upon the guard conductor thereof, corresponding to the guard conductor C322 of the finder switch 130. Accordingly, the distributor 300 operates automatically to preselect an idle link in the first group of links immediately after the previously selected link in the first group of links is taken for use by a calling line and operates to find the calling line.

It is noted that the distributor 300 operates in the above-described manner in order to preselect an idle link in the first group of links only in the event that an idle link is available in the first group of links, due to the fact that the busy transfer relay R340 is retained in its operated position at this time only in the event that ground potential is present upon the all-trunks-busy conductor C321, which condition obtains only in the event that there is an idle link available in the first group of links. In the event that all of the links in the first group of links are busy at this time, no ground potential appears upon the all-trunks-busy conductor C321, whereby the circuit for energizing the winding of the busy transfer relay R340 is interrupted in order to cause the busy transfer relay R340 to restore. Upon restoring, the busy transfer relay R340 interrupts, at RA344, a further point in the alternative holding circuit for energizing the winding thereof, interrupts, at RA345, a point in the previously traced circuit for energizing the rotary magnet M308, thereby to prevent operation of the rotary magnet M308, and interrupts, at RA341 and RC343, the connection between the start conductor C316 and the winding of the start relay R345. Also, upon restoring, the busy transfer relay R340 connects, at RA341 and RC342, the conductors C328 and C327 extending to the distributor 312. Accordingly, at this time, the

start conductor C316 extending to the distributor 300 is connected, together with the start conductor C315, to the conductor C327 extending to the distributor 312. Hence, at this time, the distributor 312 is operative to assign idle links in the second group of links to the use of calling lines in both the first and second groups of lines.

Continuing now with the release of the distributor 300 incident to the restoration of the start relay R345 and the control relay R350, when the control relay R350 restores it interrupts, at RA351, the previously traced circuit for energizing the winding of the start relay R140 in the finder switch 130. Shortly thereafter the start relay R140, being of the slow-to-release type, restores to interrupt, at RA141, the first-mentioned path between the line conductors C116 and C117 of the trunk line 115 and to complete, at RA143, an alternative path for applying ground potential to the guard conductor C322, this path extending from ground by way of the switch springs 180 and 181 of the set of switch springs S179, RA143, and the switch springs 185 and 184 of the busy switch S183 to the guard conductor C322. This application of ground potential to the guard conductor C322 insures that the distributor 300 will not operate to select the busy link 60 at this time. Also, upon restoring, the start relay R140 interrupts, at RA141, a further point in the previously traced circuit for energizing the rotary magnet M171, interrupts, at RA148, a further point in the previously traced circuit for energizing the vertical magnet M170, interrupts, at RA142, a point in the previously mentioned circuit for energizing the winding of the second test relay R325 in the distributor 300, and completes, at RA144 and RC145, the previously mentioned circuit for illuminating the supervisory lamp L128, this circuit extending from ground by way of RA144, RC145, the switch springs 186 and 187 of the busy switch S183, the switch springs 178 and 176 of the set of switch springs S175, RA166, RC167 and L128 to battery. The illumination of the supervisory lamp L128 indicates to the exchange attendant that the link 60 is busy upon a call routed therethrough.

Also, upon restoring, the control relay R350 in the distributor 300 interrupts, at RA352, the previously traced original circuit for energizing the switching relay R160 in the finder switch 130, interrupts, at RA357, a further point in the previously traced circuit for energizing the lower winding of the transfer relay R360 in the distributor 300, and interrupts, at RA356, a point in the previously traced circuit for energizing the upper winding of the transfer relay R360 and a point in the previously traced holding circuit for energizing the winding of the control relay R380, thereby to cause the transfer relay R360 and the control relay R380 to restore. Upon restoring, the transfer relay R360 interrupts, at RA369, a further point in the holding circuit for energizing the upper winding thereof, interrupts, at RA365 and RC368, a point in the previously traced circuit for energizing the winding of the first test relay R320, and prepares, at RA366 and RC367, a point in the previously traced circuit for energizing the lower winding thereof. Also, upon restoring, the transfer relay R360 prepares, at RA365, a point in the previously traced original circuit for energizing the winding of the control relay R350 in series with the rotary magnet M308, interrupts, at RA361 and RC364, a further point in the previously traced original circuit for

energizing the winding of the switching relay R160 in the finder switch 130, and prepares, at RA381 and RC382, a point in a circuit for energizing the vertical magnet in the finder switch of a selected link when the distributor 300 operates to select an idle link in the first group of links for the use of a calling line.

Upon restoring, the control relay R380 interrupts, at RA386, a further point in the holding circuit for energizing the winding thereof, interrupts, at RA385, a point in the holding circuit for energizing the upper winding of the control relay R380, thereby to cause the latter relay to restore, and interrupts, at RA382 and RC384, a further point in the holding circuit for energizing the upper winding of the transfer relay R360. Also, the control relay R380 prepares, at RA382 and RC383, a point in a circuit traced hereinafter for energizing the upper winding of the control relay R380, and interrupts, at RA381, a point in the previously traced alternative circuit for energizing the winding of the control relay R350 in series with the rotary magnet M308.

Upon restoring, the control relay R380 interrupts, at RA386, a further point in the previously traced holding circuit for energizing the lower winding thereof, interrupts, at RA387, a further point in the previously traced circuit for energizing the winding of the first test relay R320, and interrupts, at RA388, a point in the previously mentioned circuit for energizing the winding of the second test relay R325. Also, the control relay R380 interrupts, at RA383 and RC385, a further point in the holding circuit for energizing the upper winding of the transfer relay R360, prepares, at RA383 and RC384, a point in the previously traced circuit for energizing the winding of the timing relay R315, interrupts, at RA380 and RC382 a further point in the previously traced alternative circuit for energizing the winding of the control relay R350 in series with the rotary magnet M308, and prepares, at RA380 and RC381, a point in the previously traced original circuit for energizing the winding of the control relay R350 in series with the rotary magnet M308.

Upon restoring, the first test relay R320 interrupts, at RA321 and RC323, a further point in the previously traced original circuit for energizing the winding of the switching relay R160 in the finder switch 130, and prepares, at RA321 and RC322, a point in a circuit for energizing the rotary magnet in the finder switch of a pre-selected link. At this time, the distributor 300 is completely released for further use and the subscriber substation A is operatively connected by way of the previously traced circuit to the connector switch 215.

As previously noted, as soon as the finder switch 130 operates to seize the calling subscriber line 101, ground potential is applied therein to the guard conductor C322, thereby to complete the previously traced path for short-circuiting the winding of the control relay R350 in order to cause the control relay R350 to restore and initiate the release of the distributor 300. It is noted that it is not possible to re-operate the control relay R350 until the distributor 300 is completely released in spite of the fact that there may be present a calling line in the first group of lines which causes the start relay R345 to remain in its operated condition, due to the fact that, upon restoring, the control relay R350 interrupts, at RA359, the previously

traced alternative circuit for energizing the winding thereof in series with the rotary magnet M308, and the original circuit for energizing the winding of the control relay R350 in series with the rotary magnet M308 is not recompleted until subsequent to the restoration of the transfer relay R360 and the control relay R380, as previously explained. Accordingly, the distributor 300 is completely released each time a finder switch of a link selected thereby operates to find a calling line in spite of the fact that the start relay R345 therein remains operated, due to the presence of other calling lines in the first group of lines.

In the event another calling line is present in the first group of lines at this time, the start relay R345 in the distributor 300 remains in its operated position, and, when the transfer relay R360 and the control relay R380 restore, the previously traced original circuit for energizing the control relay R350 is recompleted, assuming that the rotary magnet M308 has already operated to cause the rotary switch 301 to find an idle link in the first group of links. The control relay R350 then operates, thereby to cause the finder switch of the previously selected link to operate and seize the calling subscriber line in the first group of lines, as explained above.

As previously noted, the distributor 300 is operative to cause the finder switch of a selected link in the first group of links, such as the finder switch 130 of the link 60, to operate and seize a calling line in the second group of lines, which condition may arise when all of the links in the second group of links are busy. In this event, the distributor 312 operates, thereby to cause the conductors C327 and C328 therein to be connected together, in a manner similar to that previously explained, incident to the restoration of the busy transfer relay R340 in the distributor 300 when all of the links in the first group of links are busy. At this time, ground potential applied to the start conductor C315 is extended by way of the conductor C327 and the distributor 312 to the conductor C328, in order to cause the start relay R345 in the distributor 300 to be energized and to operate in the previously described manner. The subsequent operations of the distributor 300 and the finder switch 130 of the link 60, incident to the operation of the start relay R345 in the distributor 300, are the same as previously described, assuming that the calling line in the second group of lines is also accessible to the upper wiper set of the Strowger mechanism 140 of the finder switch 130.

Furthermore, the finder switch 130 of the link 60 is operative in a manner substantially identical to that previously explained to find a calling line in either the first group of lines or the second group of lines and accessible to the lower wiper set of the Strowger mechanism 140 thereof. However, in this case, when the carriage of the Strowger mechanism 140 of the finder switch 130 is rotated in the rotary direction to the position of the contact set terminating the calling subscriber line, battery potential is encountered by the wiper 146 in the lower wiper set appearing upon the contact terminating the control conductor of the calling subscriber line. This application of battery potential to the wiper 146 completes the previously mentioned circuit for energizing the winding of the second test relay R325 in the distributor 300, this circuit extending from ground by way of RA338, the unidirectional current conducting device or copper oxide rectifier

348, the winding of the second test relay R325, the second test conductor C326, RA142, and the control conductor C138 of the trunk line 135 to battery potential appearing upon the wiper 146. When energized over the above-traced circuit, the second test relay R325 operates to interrupt, at RA326 and RC327, a point in the previously traced circuit for energizing the rotary magnet M171 in the finder switch 130, thereby to arrest further operation of the finder switch. Also, upon operating, the second test relay R325 completes, at RA328 and RC328, the previously mentioned circuit for energizing the winding of the switching relay R150 in the finder switch 130, this circuit extending from ground by way of RA352, RA371, RA361, RC364, RA321, RC322, RA326, RC328, the wiper 301 and associated contact of the rotary switch 301, the conductor C325, RA160, and the winding of R150 to battery. When energized over the above-traced circuit, the switching relay R150 operates to interrupt, at RA157, a further point in the previously traced circuit for energizing the rotary magnet M171, and to complete, at RA156, a path for applying ground potential to the guard conductor C322. The path for applying ground potential to the guard conductor C322 extends from ground by way of the switch springs 180 and 181 of the set of switch springs S179, RA156, and the switch springs 185 and 184 of the busy switch S183 to the guard conductor C322. This application of ground potential to the guard conductor C322 causes the distributor 300 to be released and the rotary switch 301 therein to operate and select an idle link in the first group of links, as previously explained.

Also, upon operating, the switching relay R150 interrupts, at RA155, a point in the previously traced circuit for energizing the winding of the switching relay R150, and completes, at RA154, a holding circuit for energizing the winding thereof, this circuit extending from the grounded control conductor C118 of the trunk line 115 by way of RA154 and the winding of R150 to battery. Finally, the switching relay R150 connects the trunk line 135 extending to the lower wiper set of the Strowger mechanism 140 to the trunk line 115. More specifically, the conductors C136, C137 and C138 of the trunk line 135 are respectively connected at RA151, RA152 and RA153 to the conductors C116, C117 and C118, respectively, of the trunk line 115. When the trunk line 135 is connected to the trunk line 115, the line circuit individually associated with the calling subscriber line and the connector switch 215 operate in the previously described manner.

It is noted that there is a possibility that the upper and lower wiper sets of the Strowger mechanism 140 of the finder switch 130 may simultaneously encounter contact sets in the contact bank terminating calling subscriber lines. In this event, the presence of battery potential appearing upon the contacts in the two contact sets respectively engaged by the wipers 143 and 146 in the upper and lower wiper sets, respectively, of the Strowger mechanism 140 complete the previously traced circuits for respectively energizing the windings of the first and second test relays R320 and R325, respectively, thereby to cause both of these test relays to operate. Upon operating, the first test relay R320 completes, at RA321 and RC323, the previously traced circuit for energizing the winding of the switching relay R160, thereby to cause the switching relay R160 to operate, and interrupts, at RA321 and RC322,

the previously traced circuit for energizing the winding of the switching relay R150, thereby to prevent operation of the switching relay R150. Accordingly, under this condition, the switching relay R160 is operated and the switching relay R150 is not operated. Hence, the finder switch 130 operates to find the calling line accessible to the upper wiper set of the Strowger mechanism 140 thereof in preference to the calling line accessible to the lower wiper set of the Strowger mechanism 140 thereof.

It is noted that, incident to operation of the finder switch 130, the wipers 143 and 146 in the upper and lower wiper sets, respectively, of the Strowger mechanism 140 may engage contacts in the contact sets in the associated contact bank terminating the control conductors of subscriber lines having either ground or booster battery potential appearing thereupon; ground potential appearing upon the control conductors of the subscriber lines when the subscriber lines are busy, and booster battery potential appearing upon the subscriber lines when the subscriber lines are being metered. When the wiper 143 of the upper wiper set of the Strowger mechanism 140 engages a contact having ground potential appearing thereupon, a path is completed for short-circuiting the winding of the first test relay R320 in the distributor 300, this circuit extending from the grounded control conductor of the subscriber line, by way of the wiper 143 and the associated contact, C134, the first test conductor C317, the wiper 302 and associated contact of the rotary switch 301, RA366, RC368, the winding of R320, the copper oxide rectifier 347, and RA337 to ground. When the wiper 143 of the upper wiper set of the Strowger mechanism 140 engages a contact having booster battery potential appearing thereupon, a circuit is completed substantially identical to the above-traced path, tending to energize the winding of the first test relay R320. However, the copper oxide rectifier 347 is so connected and arranged that current is prevented from traversing this circuit in a direction extending from the wiper 143 to ground at RA337. Accordingly, the first test relay R320 is not effectively energized. Thus, the first test relay R320 does not operate when the wiper 143 of the upper wiper set of the Strowger mechanism 140 engages a contact terminating the control conductor of a subscriber line having either ground or booster battery potential appearing thereon.

In a similar manner, a path is completed for short-circuiting the winding of the second test relay R325 when the wiper 146 in the lower wiper set of the Strowger mechanism 140 engages a contact terminating a control conductor of a subscriber line having ground potential appearing thereon; and a circuit is completed tending to energize the winding of the second test relay R325 when the wiper 146 engages a contact terminating a control conductor of a subscriber line having booster battery potential appearing thereon. However, the copper oxide rectifier 348 prevents the winding of the second test relay R325 from being effectively energized in the last-mentioned case. Hence, the arrangements of the copper oxide rectifiers 347 and 348 in the circuits for respectively energizing the windings of the first and second test relays R320 and R325, respectively, prevent false operation of the finder switch 130 and the consequent seizure thereby of a busy subscriber line having booster battery

potential appearing upon the control conductor thereof.

In the foregoing description of the operation of the finder switch 130 of the link 60 to seize the calling subscriber line 101, it was assumed that the finder switch 130 operated properly to seize this calling subscriber line. However, it may occur that the finder switch 130 fails to operate properly to seize the calling subscriber line 101 when the operation thereof is initiated by the distributor 300, due to the fact that the finder switch 130 has become temporarily inoperative. In this event, the finder switch 130 fails to seize the calling subscriber line 101. Accordingly, ground potential is not applied in the finder switch 130 to the guard conductor C322 in order to cause the distributor 300 to be released, as previously explained. Hence, after a predetermined time interval, the vibratory armature RA376 of the timing relay R375 in the distributor 300 assumes an intermediate position with respect to the associated contacts RC377 and RC378, thereby to interrupt the previously traced holding circuit for energizing the winding of the control relay R380 in order to cause the control relay R380 to restore. Upon restoring, the control relay R380 interrupts, at RA382 and RC384, the previously traced holding circuit for energizing the upper winding of the transfer relay R360, and completes, at RA382 and RC383, a point in the previously mentioned circuit for energizing the upper winding of the control relay R390. The circuit for energizing the upper winding of the control relay R390 extends from ground by way of RA356, RA333, RC335, RA382, RC383, and the upper winding of R390 to battery. When energized over the above-traced circuit, the control relay R390 operates to complete, at RA392, a holding circuit for energizing the lower winding thereof, this circuit extending from the grounded conductor C330 by way of the switch springs 338 and 337 of the busy switch S334, RA392 and the lower winding of R390 to battery. It is noted that ground potential appears upon the conductor C330 in the distributor 312 so long as ground potential appears upon the all-trunks-busy conductor associated with the finder switches of the links in the second group of links, just as ground potential appears upon the conductor C329 in the distributor 300 so long as ground potential appears upon the all-trunks-busy conductor C321 associated with the finder switches of the links in the first group of links. Also, upon operating, the relay R390 completes, at RA391, a path for short-circuiting the winding of the control relay R350, this path extending from the upper terminal of the winding of R350 by way of RA391, RA353, RC355, MA308, RA345, and the winding of R350 to the upper terminal thereof. When the winding of the control relay R350 is thus short-circuited, the control relay R350 restores to interrupt, at RA353 and RC355, a point in the previously traced path for short-circuiting the winding thereof, and to complete, at RA353 and RA354, an alternative path for short-circuiting the winding thereof. The alternative path for short-circuiting the winding of the control relay R350 extends from the upper terminal of the winding of R350 by way of RA391, RA353, RC354, and the winding of R350 to the upper terminal thereof. Also, upon restoring, the control relay R350 interrupts, at RA358, a point in the previously traced alternative circuit for energizing the winding of the busy transfer relay R340.

Also, upon operating, the control relay R380 interrupts, at RA383, the previously traced original circuit for energizing the winding of the busy transfer relay R340, and interrupts, at 5 RA384, the normal connection between the conductor C329 extending into the distributor 312 and the winding of the busy transfer relay R340, thereby to cause the busy transfer relay R340 to restore and to insure that it remains in its restored position. Upon restoring, the busy transfer relay R340 completes, at RA341 and RC342, the previously mentioned connection between the conductors C327 and C328 extending to the distributor 312, thereby to cause the distributor 312 to assign links in the second group of links to the use of calling lines in both the first and second groups of lines, as previously explained.

Also, upon operating, the control relay R380 completes, at RA382, a circuit for illuminating 20 the supervisory lamp L309, this circuit extending from the grounded conductor C330 by way of the switch springs 338 and 337 of the busy switch S334, RA382, and the lamp L309 to battery. Illumination of the supervisory lamp L309 indicates to the exchange attendant that the distributor 300 is locked out of service. The release of the remainder of the operated relays in the distributor 300, incident to the restoration of the control relay R350 and the busy transfer relay R340, is the same as that previously described. At this time, the distributor 300 is locked out of service, as previously noted.

It is noted that the distributor 300 remains 35 locked out of service until the busy switch S334 is operated away from its normal position and returned thereto, which switch will not be thus operated until the defective finder switch of one of the links in the first group of links is found and again placed in working order. When the busy switch S334 is operated away from its normal position, the switch springs 337 and 338 are actuated into disengagement, thereby to interrupt the previously traced holding circuit for energizing the lower winding of the control relay R390 in order to cause the control relay R390 to restore. Upon restoring, the control relay R390 reconnects, at RA394, the conductor C329 extending into the distributor 312 to the winding of the busy transfer relay R340, and prepares, at RA393, a point in the previously traced original circuit for energizing the winding of the busy transfer relay R340 by way of the all-trunks-busy conductor C321. When the busy switch S334 is returned to its normal position, there is completed at the switch springs 335 and 336 50 thereof the previously traced original circuit for energizing the winding of the busy transfer relay R340 by way of the all-trunks-busy conductor C321, in the event one of the links in the first group of links is idle at this time, as previously explained.

It is noted that the finder switch 130 of the link 60 embodies an arrangement for causing the distributor 300 to select another idle link in the first group of links for the use of the calling subscriber line 101 in the event that the finder switch 130 of the selected link 60 in the first group of links fails to find the calling line 101 incident to the operation thereof. More particularly, the set of switch springs S174 in the 55 finder switch 130 is actuated into engagement when the carriage of the Strowger mechanism 140 of the finder switch 130 is driven eleven steps in the rotary direction away from its normal position, due to the failure of the finder switch 70 75

130 to find the calling line 101. When the set of switch springs S174 is actuated into engagement, a path is completed for applying ground potential to the guard conductor C322, this path extending from ground by way of the set of switch springs S174, the switch springs 185 and 184 of the busy switch S183 to the guard conductor C322. This application of ground potential to the guard conductor C322 completes the previously traced circuit for energizing the rotary magnet M308 and for short-circuiting the winding of the control relay R150, thereby to cause the distributor 300 to release and to cause the rotary switch 301 therein to operate and select another idle link in the first group of links for the use of the calling subscriber line 101, in the previously described manner.

It is noted that the finder switch 130 of the link 60 may be rendered busy by operating the busy switch S183. When the busy switch S183 is operated, the switch springs 186, 187 and 184, 185 thereof are actuated into disengagement, and the switch springs 186, 184 thereof are actuated into engagement. When the switch springs 186 and 187 of the busy switch S183 are actuated into disengagement, the previously traced path for applying ground potential in the finder switch 130 to the all-trunks-busy conductor C321 is interrupted; when the switch springs 184 and 185 of the busy switch S183 are actuated into disengagement, a point in the previously traced path for applying ground potential to the guard conductor C322, incident to the operation of the switching relays R150 and R160, is interrupted; and, when the switch springs 186 and 184 of the busy switch S183 are actuated into engagement, a path is completed in the finder switch 130 for applying ground potential to the guard conductor C322. The last-mentioned path for applying ground potential to the guard conductor C322 extends from ground by way of RA144, RC145, and the switch springs 186 and 184 of the busy switch S183, to the guard conductor C322. This application of ground potential to the guard conductor C322 marks the link 60 as busy, thereby to prevent the distributor 300 from selecting the link 60 in the first group of links, or causes the rotary switch 301 in the distributor 300 to operate and select another idle link in the first group of links in the event that the distributor 300 has previously operated to select the link 60 prior to the operation of the busy switch S183 therein. In the event the distributor 300 has operated to select the link 60 in the first group of links prior to operation of the busy switch S183 therein, as explained above, the application of ground potential to the guard conductor C322, incident to the operation of the busy switch S183, causes the rotary switch 301 in the distributor 300 to operate and select another idle link in the first group of links. Specifically, this application of ground potential to the guard conductor C322 completes the previously traced circuit for energizing the rotary magnet M308 of the rotary switch 301 in the distributor 300. The operation of the rotary magnet M308 to cause the rotary switch 301 to select an idle link in the first group of links is the same as that previously explained.

In view of the foregoing explanation of the mode of operation of the distributor 300 to assign idle links in the first group of links to the use of calling lines, it will be understood that the distributor 312 is operative in an identical manner to assign idle ones of the links in the

second groups of links to the use of calling lines. Again it is noted that the links in the first group of links are normally assigned to the use of calling lines in the first group of lines, but are assigned to the use of calling lines in both the first group of lines and the second group of lines when all of the links in the second group of lines are busy; while the links in the second group of links are normally assigned to the use of the calling lines in the second group of lines, but are assigned to the use of calling lines in both the first group of lines and the second group of lines when all of the links in the first group of links are busy.

15 Further it is noted that the lines in the first group of lines are terminated in the first five levels of the Strowger mechanisms of the finder switches in the first group of links; while the lines in the second group of lines are terminated in the second five levels of the Strowger mechanisms of the finder switches in the first group of links. Conversely, the lines in the first group of lines are terminated in the second five levels of the Strowger mechanisms of the finder switches in the second group of links; while the lines in the second group of lines are terminated in the first five levels of the Strowger mechanisms of the finder switches in the second group of links. Thus it will be understood that the 20 levels 1, 2, 3, 4 and 5 in the Strowger mechanisms of the finder switches in the first group of links correspond respectively to the levels 10, 9, 8, 7 and 6 in the Strowger mechanisms of the finder switches in the second group of links, the 25 levels mentioned terminating the lines in the first group of lines; while the levels 6, 7, 8, 9 and 10 in the Strowger mechanisms of the finder switches in the first group of links correspond respectively to the levels 5, 4, 3, 2 and 1 in the 30 Strowger mechanism of the finder switches in the second group of links, the levels mentioned terminating the lines in the second group of lines. Accordingly, it will be understood that the fifth and sixth levels in the Strowger mechanisms of 35 the finder switches in the first group of links respectively correspond to the sixth and fifth levels in the Strowger mechanisms of the finder switches in the second group of links.

Considering now the operation of both the distributor 300 and the distributor 312, it is noted that a first path or blocking circuit is provided for applying ground potential to the contacts in the fifth level of the Strowger mechanisms of the 40 finder switches in the first group of links, which path extends, when completed, from ground by way of RA387, C201, RA340' and C204 to the level mentioned; while a second path or blocking circuit is provided for applying ground potential to the contacts in the fifth level of the Strowger mechanisms of the 45 finder switches in the second group of links, which path extends, when completed, from ground by way of RA387', C292, RA340 and C203 to the level mentioned. Further it is noted that the control relay R380 and the 50 busy transfer relay R340 in the distributor 300 respectively correspond to the control relay R380' and the busy transfer relay R340' in the distributor 312.

As previously explained, the busy transfer relay R340 in the distributor 300 occupies its operated position while there is an idle link in the first group of links or while the distributor 300 is operating; while the control relay R380 in the distributor 300 occupies its operated position only 55 while the distributor 300 is operating. Similarly,

the busy transfer relay R340' in the distributor 312 occupies its operated position while there is an idle link in the second group of links or while the distributor is operating; while the control relay R380' in the distributor 312 occupies its operated position only while the distributor 312 is operating. Accordingly, the first path for applying ground potential to the contacts in the fifth level of the Strowger mechanisms of the finder switches in the first group of links is completed when the control relay R380 in the distributor 300 and the busy transfer relay R340' in the distributor 312 occupy their operated positions, which condition prevails while the distributor 300 is operating, and when there is an idle link in the second group of links or while the distributor 312 is operating; while the second path for applying ground potential to the contacts in the fifth level of the Strowger mechanisms of the finder switches in the second group of links is completed when the control relay R380', in the distributor 312 and the busy transfer relay R340 in the distributor 300 occupy their operated positions, which condition prevails while the distributor 312 is operating, and when there is an idle link in the first group of links or while the distributor 300 is operating.

When the first path for applying ground potential to the contacts in the fifth level of the Strowger mechanisms of the finder switches in the first group of links is completed, the Strowger mechanisms of the finder switches of the links in the first group of links are positively prevented from operating beyond the fifth level thereof due to the presence of ground potential upon the contacts in the fifth level thereof, thereby rendering the lines in the second group of lines non-selectable by the Strowger mechanisms of the finder switches in the first group of links at this time. More specifically, the application of ground potential to the contacts in the fifth level of the Strowger mechanisms of the finder switches in the first group of links is effective to cause operation of the transfer relay R360 in the distributor 300 and the consequent arresting of the operation of the vertical magnet in the Strowger mechanism of the finder switch of the link assigned for use at this time, in the event the Strowger mechanism of the finder switch of the link assigned for use at this time is operated to the fifth level thereof. The rotary magnet in the Strowger mechanism of the finder switch of the link assigned for use at this time is then operated, thereby to cause the Strowger mechanism of the finder switch of the link mentioned to seize a calling line in the fifth level thereof or the finder switch of the last-mentioned link to be released in the manner previously explained.

Similarly, when the second path for applying ground potential to the contacts in the fifth level of the Strowger mechanisms of the finder switches in the second group of links is completed, the Strowger mechanisms of the finder switches of the links in the second group of links are positively prevented from operating beyond the fifth level thereof due to the presence of ground potential upon the contacts in the fifth level thereof, thereby rendering the lines in the first group of lines non-selectable by the Strowger mechanisms of the finder switches in the second group of links at this time. More specifically, the application of ground potential to the contacts in the fifth level of the Strowger mechanisms of the finder switches in the second group of links is effective to cause operation of the transfer relay,

not shown, in the distributor 312 and the consequent arresting of the operation of the vertical magnet in the Strowger mechanism of the finder switch of the link assigned for use at this time, in the event the Strowger mechanism of the finder switch of the link assigned for use at this time is operated to the fifth level thereof. The rotary magnet in the Strowger mechanism of the finder switch of the link assigned for use at this time is then operated, thereby to cause the Strowger mechanism of the finder switch of the link mentioned to seize a calling line in the fifth level thereof or the finder switch of the last-mentioned link to be released in the manner previously explained.

In view of the foregoing explanation of the mode of operation of the distributors 300 and 312, it will be understood that, when all of the links in the first group of links are rendered busy and the distributor 300 is released, the busy transfer relay R340 in the distributor 300 restores, thereby to transfer the first start conductor C316 to the distributor 312 and to interrupt, at RA340, the second path for applying ground potential to the contacts in the fifth level of the Strowger mechanisms of the finder switches in the second group of links, thereby to render the Strowger mechanisms of the finder switches in the second group of links operative to seize a calling line in either the second group of lines or the first group of lines; similarly, when all of the links in the second group of links are rendered busy and the distributor 312 is released, the busy transfer relay R340' in the distributor 312 restores, thereby to transfer the second start conductor C315 to the distributor 300 and to interrupt, at RA340', the first path for applying ground potential to the contacts in the fifth level of the Strowger mechanisms of the finder switches in the first group of links, thereby to render the Strowger mechanisms of the finder switches in the first group of links operative to seize a calling line in either the first group of lines or the second group of lines. Further it is noted that, when the distributor 300 is not operating, the control relay R380 therein restores, thereby to interrupt, at RA387, the first path for applying ground potential to the contacts in the fifth level of the Strowger mechanisms of the finder switches in the first group of links; similarly, when the distributor 312 is not operating, the control relay R380' therein restores, thereby to interrupt, at RA387', the second path for applying ground potential to the contacts in the fifth level of the Strowger mechanisms of the finder switches in the second group of links.

In view of the foregoing description of the mode of operation of the distributors 300 and 312, it will be understood that the connection and arrangement thereof positively prevent simultaneous seizure of a calling line in one of the groups of lines by the Strowger mechanisms of finder switches of two links in the respective groups of links incident to the abandonment of a call on a line in the other of the groups of lines. For example, in the event calls are initiated on two lines in the respective first and second groups of lines, operation of the distributors 300 and 312 are initiated, whereupon operation of the Strowger mechanisms of finder switches of two links in the respective groups of links are initiated. Now in the event the call on the line in the second group of lines is abandoned, the Strowger mechanism of the finder switch in the second group of links is arrested

when it is operated to the fifth level thereof due to the completed second path for applying ground potential to the contacts in the fifth level of the Strowger mechanisms of the finder switches in the second group of links; accordingly, there is no interference by the Strowger mechanism of the finder switch of the link in the second group of links with the operation of the Strowger mechanism of the finder switch of the link in the first group of links. On the other hand, in the event the call on the line in the first group of lines is abandoned the Strowger mechanism of the finder switch in the first group of links is arrested when it is operated to the fifth level thereof due to the completed first path for applying ground potential to the contacts in the fifth level of the Strowger mechanisms of the finder switches in the first group of links; accordingly, there is no interference by the Strowger mechanism of the finder switch of the link in the second group of links with the operation of the Strowger mechanism of the finder switch of the link in the first group of links. In other words, the distributors 300 and 312 are so connected and arranged that a line in the first group of lines is not selectable by the finder switch of a link in the second group of links while the distributor 300 is operating; while a line in the second group of lines is not selectable by the finder switch of a link in the first group of lines while the distributor 312 is operating.

Continuing now with the operation of the connector switch 215 to extend a call from the subscriber substation A to the subscriber substation B, when the finder switch 130 operates to seize the calling subscriber line 101, the connector switch 215 is rendered operative in response to digits transmitted thereto from the subscriber substation A.

The subscriber at the substation A then dials the digits of the directory number of the called subscriber substation B at the dial mechanism at the substation A, thereby to transmit a number of series of impulses by way of the subscriber loop circuit to the connector switch 215, in order to cause the connector switch 215 to operate, in the usual manner, and seize the called subscriber line 230. In the event the called subscriber line 230 is busy, ground potential appears upon the control conductor C234 thereof, thereby to cause the connector switch 215 to operate and return busy tone current over the loop circuit extending to the calling subscriber substation A, in the usual manner. On the other hand, in the event the called subscriber line 230 is idle, battery potential appears upon the control conductor C234 thereof.

The connector switch 215 then operates to cause direct ground potential to be applied to the control conductor C234 of the telephone line 230, thereby to mark the telephone line 230 busy to the connector switches having access thereto.

After seizing the called subscriber line 230, the connector switch 215 operates to cause ringing current to be projected over the line conductors C231 and C232 of the subscriber line 230 in the usual manner, thereby to cause the ringer at the called substation B to operate. When the subscriber at the substation B answers the call by removing the telephone receiver of the telephone instrument thereat from its associated switchhook, a loop circuit is completed by way of the line conductors of the subscriber line 230 to the connector switch 215, thereby to cause a battery reversing relay in the connector switch

215 to operate in the usual manner. Also, the connector switch 215 operates to complete a connection between the calling subscriber loop circuit extending thereto from the subscriber substation A and the called subscriber loop circuit extending thereto from the substation B, whereupon an established connection is completed between the calling subscriber substation A and the called subscriber substation B.

10 The release of the established connection between the subscriber substations A and B is under the control of the subscribers thereat and, when both of the subscribers replace the receivers of the telephone instruments upon their associated switchhooks at the substations A and B, the connector switch 215 first releases. When the connector switch 215 is released, ground potential is removed from the control conductor C118 of the trunk line 115. When ground potential is removed from the control conductor C118 of the trunk line 115, the previously traced circuit for energizing the winding of the switching relay R160 in the finder switch 130 is interrupted, thereby to cause the latter relay to restore. Upon restoring, the switching relay R160 prepares, at RA165, a point in the previously traced circuit for energizing the rotary magnet M171, interrupts, at RA169, a point in the previously traced path for applying ground potential to the guard conductor C322, interrupts, at RA164, a further point in the holding circuit for energizing the winding thereof, prepares, at RA160, a point in the previously traced circuit for energizing the winding of the switching relay R150, and interrupts, at RA161, RA162 and RA163, the connection between the trunk line 115 and the trunk line 131. Also, upon restoring, the switching relay R160 interrupts, at RA166 and RC167, the previously traced circuit for illuminating the supervisory lamp L128, and completes, at RA166 and RC168, the previously mentioned circuit for energizing the release magnet M172. The last-mentioned circuit extends from ground by way of RA144, RC145, the switch springs 186 and 187 of the busy switch 183, the switch springs 178 and 176 of the set of switch springs S175, RA166, RC168, RA158, and the release magnet M172 to battery. When energized over the above-traced circuit, the release magnet M172 operates, thereby to release the carriage of the Strowger mechanism 140 and to cause it to be returned to its normal position. When the carriage of the Strowger mechanism is returned to its normal position, the sets of switch springs S175 and S179 are actuated. More particularly, the switch springs 180 and 181 of the set of switch springs S179 are actuated into disengagement, thereby to interrupt a further point in the previously traced path for applying ground potential to the guard conductor C322; the switch springs 181 and 182 are actuated into engagement, thereby to connect the guard conductor C322 to the control conductor C118 of the trunk line 115; the switch springs 176 and 178 of the set of switch springs S175 are actuated into disengagement, thereby to interrupt the previously traced circuit for energizing the release magnet M172; and the switch springs 177 and 178 of the set of switch springs S175 are actuated into engagement, thereby to complete the previously traced path for applying ground potential in the finder switch 130 to the all-trunks-busy conductor C321. The previously mentioned connection between the guard conductor C322 and the control conductor C118 of the trunk line

115 extends from the guard conductor C322, by way of the switch springs 184 and 185 of the busy switch S183, RA143, and the switch springs 181 and 182 of the set of switch springs S179 to the control conductor C118 of the trunk line 5 115. The connection of the guard conductor C322 to the control conductor C118 of the trunk line 115 insures that the link 88 will not be selected by the distributor 388 for the use of a calling one of the lines unless both the finder 10 switch 138 and the connector switch 215 thereof are completely released. At this time, the finder switch 138 is completely released. Accordingly, the link 88 is completely released and is available to be selected by the distributor 388 for the use 15 of a calling one of the lines.

When ground potential is removed from the control conductor C118 of the trunk line 115, the previously traced circuit for energizing the winding of the cutoff relay R110 in the line circuit 20 100 individually associated with the subscriber line 101 is interrupted, thereby to cause the latter relay to restore. Upon restoring, the cutoff relay R110 interrupts, at RA113, a further point in the holding circuit for energizing the winding 25 thereof and prepares, at RA111 and at RA112, points in the previously traced circuit for energizing the winding of the line relay R120. At this time, the line circuit 100 is completely released and the subscriber line 101 is marked as 30 idle to the connector switches having access thereto.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, first and second groups of lines, first and second finder switches, each of said finder switches having access to each of the lines in each of said groups of lines and being operative to find a calling line accessible thereto, first blocking means normally effective positively to prevent said first finder switch from finding a line in said second group of lines, second blocking means normally effective positively to prevent said second finder switch from finding a line in said first group of lines, first start means operative to initiate operation of said first finder switch, means for arresting operation of and for rendering busy said first finder switch when a line is found thereby, means governed when said first finder switch is rendered busy for rendering ineffective said second blocking means, second start means operative to initiate operation of said second finder switch, means for arresting operation of and for rendering busy said second finder switch when a line is found thereby, means governed when said second finder switch is rendered busy for rendering ineffective said first blocking means, and means governed in response to the presence of a calling line in said first group of lines for operating said first start means in the event said first finder switch is idle and for operating said second start means in the event said first finder switch is busy.

2. In a telephone system, first and second groups of lines, first and second finder switches, each of said finder switches having access to each of the lines in each of said groups of lines and being operative to find a calling line accessible thereto, first blocking means operative to prevent said first finder switch from finding a line in said second group of lines, second blocking means operative to prevent said second finder switch from finding a line in said first group of lines, first start means operative to initiate operation of said first finder switch, means for arresting operation of said first finder switch when a line is found thereby, second start means operative to initiate operation of said second finder switch, means for arresting operation of said second finder switch when a line is found thereby, means governed while both said first finder switch and said second finder switch are operating for operating both said first blocking means and said second blocking means, and means governed in response to the presence of a calling line in said first group of lines for operating said first start means in the event said first finder switch is idle and for operating said second start means in the event said first finder switch is busy and governed in response to the presence of a calling line in said second group of lines for operating said second start means in the event said second finder switch is idle and for operating said first start means in the event said second finder switch is busy.

3. In a telephone system, first and second groups of lines, first and second finder switches, each of said finder switches having access to each of the lines in each of said groups of lines and being operative to find a calling line accessible thereto, first blocking means operative to prevent said first finder switch from finding a line in said 35 second group of lines, second blocking means operative to prevent said second finder switch from finding a line in said first group of lines, first start means operative to initiate operation of said first finder switch, means for arresting 40 operation of and for rendering busy said first finder switch when a line is found thereby, means governed while said first finder switch is operating and when said second finder switch is idle for operating said first blocking means, second start means operative to initiate operation of said second finder switch, means for arresting 45 operation of and for rendering busy said second finder switch when a line is found thereby, means governed while said second finder switch is operating and when said first finder switch is idle for operating said second blocking means, and means governed in response to the presence of a calling line in said first group of lines for operating 50 said first start means in the event said first finder switch is idle and for operating said second start means in the event said second finder switch is idle for operating said first blocking means, second start means operative to initiate operation of said second finder switch, means for arresting 55 operation of and for rendering busy said second finder switch when a line is found thereby, means governed while said second finder switch is operating and when said first finder switch is idle for operating said second blocking means, and means governed in response to the presence of a calling line in said first group of lines for operating 60 said first start means in the event said first finder switch is idle and for operating said second start means in the event said second finder switch is idle for operating said first blocking means, second start means in the event said first finder switch is busy and governed in response to the presence of a calling line in said second group of lines for operating 65 said second start means in the event said second finder switch is idle and for operating said first start means in the event said second finder switch is busy.

4. In a telephone system, first and second groups of lines, first and second finder switches, each of said finder switches having access to each of the lines in each of said groups of lines and being operative to find a calling line accessible thereto, first blocking means operative to prevent said first finder switch from finding a line 70 in said second group of lines, second blocking

means operative to prevent said second finder switch from finding a line in said first group of lines, first start means operative to initiate operation of said first finder switch, means for arresting operation of and for rendering busy said first finder switch when a line is found thereby, means governed while said first finder switch is operating and when said second finder switch is idle for operating said first blocking means, second start means operative to initiate operation of said second finder switch, means for arresting operation of and for rendering busy said second finder switch when a line is found thereby, means governed while said second finder switch is operating and when said first finder switch is idle for operating said second blocking means, additional means governed while both said first finder switch and said second finder switch are operating for operating both said first blocking means and said second blocking means, and means governed in response to the presence of a calling line in said first group of lines for operating said first start means in the event said first finder switch is idle and for operating said second start means in the event said first finder switch is busy and governed in response to the presence of a calling line in said second group of lines for operating said second start means in the event said second finder switch is idle and for operating said first start means in the event said second finder switch is busy.

5. In a telephone system, first and second groups of lines, first and second groups of finder switches, each of the finder switches in each of said groups of finder switches having access to each of the lines in each of said groups of lines and being operative to find a calling line accessible thereto, first blocking means normally effective positively to prevent the finder switches in said first group of finder switches from finding lines in said second group of lines, second blocking means normally effective positively to prevent the finder switches in said second group of finder switches from finding lines in said first group of lines, a first distributor operative to assign idle ones of the finder switches in said first group of finder switches in a predetermined order and to initiate operation of an assigned one of said last-mentioned finder switches, means for arresting operation of and for rendering busy said last-mentioned finder switch when a line is found thereby, means governed when all of the finder switches in said first group of finder switches are rendered busy for rendering ineffective said second blocking means, a second distributor operative to assign idle ones of the finder switches in said second group of finder switches in a predetermined order and to initiate operation of an assigned one of said last-mentioned finder switches, means for arresting operation of and for rendering busy said last-mentioned finder switch when a line is found thereby, means governed when all of the finder switches in said second group of finder switches are rendered busy for rendering ineffective said first blocking means, and means governed in response to the presence of a calling line in said first group of lines for operating said first distributor in the event there is an idle finder switch in said first group of finder switches and for operating said second distributor in the event all of the finder switches in said first group of finder switches are busy and governed in response to the presence of a calling line in said second group of lines for

operating said second distributor in the event there is an idle finder switch in said second group of finder switches and for operating said first distributor in the event all of the finder switches in said second group of finder switches are busy.

6. In a telephone system, first and second groups of lines, first and second groups of finder switches, each of the finder switches in each of said groups of finder switches having access to each of the lines in each of said groups of lines and being operative to find a calling line accessible thereto, first blocking means operative to prevent the finder switches in said first group of finder switches from finding lines in said second group of lines, second blocking means operative to prevent the finder switches in said second group of finder switches from finding lines in said first group of lines, a first distributor operative to assign idle ones of the finder switches in said first group of finder switches in a predetermined order and to initiate operation of an assigned one of said last-mentioned finder switches, means for arresting operation of and for rendering busy said last-mentioned finder switch when a line is found thereby, a second distributor operative to assign idle ones of the finder switches in said second group of finder switches in a predetermined order and to initiate operation of an assigned one of said last-mentioned finder switches, means for arresting operation of and for rendering busy said last-mentioned finder switch when a line is found thereby, means governed when a finder switch in said first group of finder switches and a finder switch in said second group of finder switches are operating for operating both said first blocking means and said second blocking means, and means governed in response to the presence of a calling line in said first group of lines for operating said first distributor in the event there is an idle finder switch in said first group of finder switches and for operating said second distributor in the event all of the finder switches in said first group of finder switches are busy and governed in response to the presence of a calling line in said second group of lines for operating said second distributor in the event there is an idle finder switch in said second group of finder switches and for operating said first distributor in the event all of the finder switches in said second group of finder switches are busy.

55 7. In a telephone system, first and second groups of lines, first and second groups of finder switches, each of the finder switches in each of said groups of finder switches having access to each of the lines in each of said groups of lines and being operative to find a calling line
60 accessible thereto, first blocking means operative to prevent the finder switches in said first group of finder switches from finding lines in said second group of lines, second blocking means operative to prevent the finder switches
65 in said second group of finder switches from finding lines in said first group of lines, a first distributor operative to assign idle ones of the finder switches in said first group of finder switches in a predetermined order and to initiate operation of an assigned one of said last-mentioned finder switches, means for arresting operation of and for rendering busy said last-mentioned finder switch when a line is found thereby, means governed while a finder switch
70 in said first group of finder switches is operating
75

first group of finder switches in a predetermined order and to initiate operation of an assigned one of said last-mentioned finder switches, means for arresting operation of and for rendering busy said last-mentioned finder switch when a line is found thereby, a second distributor operative to assign idle ones of the finder switches in said second group of finder switches in a predetermined order and to initiate operation of an assigned one of said last-mentioned finder switches, means for arresting operation of and for rendering busy said last-mentioned finder switch when a line is found thereby, means included in said first distributor and governed when a finder switch in said first group of finder switches is operating for preparing points in both said first blocking circuit and said second blocking circuit, means included in said second distributor and governed when a finder switch in said second group of finder switches is operating for preparing points in both said first blocking circuit and said second blocking circuit, each of said blocking circuits being completed only when points are prepared therein in both said first distributor and said second distributor, and means governed in response to the presence of a calling line in said first group of lines for operating said first distributor in the event there is an idle finder switch in said first group of finder switches and for operating said second distributor in the event all of the finder switches in said first group of finder switches are busy and governed in response to the presence of a calling line in said second group of lines for operating said second distributor in the event there is an idle finder switch in said second group of finder switches and for operating said first distributor in the event all of the finder switches in said second group of finder switches are busy.

14. In a telephone system, first and second groups of lines, first and second groups of finder switches, each of the finder switches in each of said groups of finder switches having access to each of the lines in each of said groups of lines and being operative to find a calling line accessible thereto, a first blocking circuit adapted to be completed to prevent the finder switches in said first group of finder switches from finding lines in said second group of lines, a second blocking circuit adapted to be completed to prevent the finder switches in said second group of finder switches from finding lines in said first group of lines, a first distributor operative to assign idle ones of the finder switches in said first group of finder switches in a predetermined order and to initiate operation of an assigned one of said last-mentioned finder switches, means for arresting operation of and for rendering busy said last-mentioned finder switch when a line is found thereby, a second distributor operative to assign idle ones of the finder switches in said second group of finder switches in a predetermined order and to initiate operation of an assigned one of said last-mentioned finder switches, means for arresting operation of and for rendering busy said last-mentioned finder switch when a line is found thereby, means included in said first distributor and governed while a finder switch in said first group of finder switches is operating for preparing a point in said first blocking circuit, additional means included in said first distributor and governed when there is an idle finder switch in said first group of finder switches for prepar-

ing a point in said second blocking circuit, means included in said second distributor and governed while a finder switch in said second group of finder switches is operating for preparing a point in said second blocking circuit, additional means included in said second distributor and governed when there is an idle finder switch in said second group of finder switches for preparing a point in said first blocking circuit, each of said blocking circuits being completed only when points are prepared therein in both said first distributor and said second distributor, and means governed in response to the presence of a calling line in said first group of lines for operating said first distributor in the event there is an idle finder switch in said first group of finder switches and for operating said second distributor in the event all of the finder switches in said first group of finder switches are busy and governed in response to the presence of a calling line in said second group of lines for operating said second distributor in the event there is an idle finder switch in said second group of finder switches and for operating said first distributor in the event all of the finder switches in said second group of finder switches are busy.

15. In a telephone system, first and second groups of lines, first and second groups of finder switches, each of the finder switches in each of said groups of finder switches having access to each of the lines in each of said groups of lines and being operative to find a calling line accessible thereto, a first blocking circuit adapted to be completed to prevent the finder switches in said first group of finder switches from finding lines in said second group of lines, a second blocking circuit adapted to be completed to prevent the finder switches in said second group of finder switches from finding lines in said first group of lines, a first distributor operative to assign idle ones of the finder switches in said first group of finder switches in a predetermined order and to initiate operation of an assigned one of said last-mentioned finder switches, means for arresting operation of and for rendering busy said last-mentioned finder switch when a line is found thereby, a second distributor operative to assign idle ones of the finder switches in said second group of finder switches in a predetermined order and to initiate operation of an assigned one of said last-mentioned finder switches, means for arresting operation of and for rendering busy said last-mentioned finder switch when a line is found thereby, means included in said first distributor and governed while a finder switch in said first group of finder switches is operating for preparing a point in said first blocking circuit, additional means included in said first distributor and governed while a finder switch in said first group of finder switches is operating or when there is an idle finder switch in said first group of finder switches for preparing a point in said second blocking circuit, means included in said second distributor and governed while a finder switch in said second group of finder switches is operating for preparing a point in said second blocking circuit, additional means included in said second distributor and governed while a finder switch in said second group of finder switches is operating or when there is an idle finder switch in said second group of finder switches for preparing a point in said first blocking circuit, each of said blocking circuits being completed only

when points are prepared therein in both said first distributor and said second distributor, and means governed in response to the presence of a calling line in said first group of lines for operating said first distributor in the event there is an idle finder switch in said first group of finder switches and for operating said second distributor in the event all of the finder switches in said first group of finder switches are busy and governed in response to the presence of a calling line in said second group of lines for operating said second distributor in the event there is an idle finder switch in said second group of finder switches and for operating said first distributor in the event all of the finder switches in said second group of finder switches are busy.

16. In a telephone system, first and second groups of lines, first and second finder switches, each of said finder switches comprising a contact bank including first and second groups of contact sets and an associated wiper set having access to the first and second groups of contact sets in the contact bank, the lines in said first group of lines being terminated by the contact sets in the first group of contact sets in the contact bank of said first finder switch and by the contact sets in the second group of contact sets in the contact bank of said second finder switch, the lines in said second group of lines being terminated by the contact sets in the second group of contact sets in the contact bank of said first finder switch and by the contact sets in the first group of contact sets in the contact bank of said second finder switch, the wiper set of each of said finder switches being operative to select a contact set accessible thereto in the associated contact bank terminating a calling line, first blocking means normally effective positively to prevent the wiper set of said first finder switch from selecting a contact set in the second group of contact sets in the associated contact bank, second blocking means normally effective positively to prevent the wiper set of said second finder switch from selecting a contact set in the second group of contact sets in the associated contact bank, first start means operative to initiate operation of the wiper set of said first finder switch, means for arresting operation of the wiper set of said first finder switch and for rendering busy said first finder switch when the wiper set thereof selects a contact set in the associated contact bank terminating a calling line, means governed when said first finder switch is rendered busy for rendering ineffective said second blocking means, second start means operative to initiate operation of the wiper set of said second finder switch, means for arresting operation of the wiper set of said second finder switch and for rendering busy said second finder switch when the wiper set thereof selects a contact set in the associated contact bank terminating a calling line, means governed when said second finder switch is rendered busy for rendering ineffective said first blocking means, and means governed in response to the presence of a calling line in said first group of lines for operating said first start means in the event said first finder switch is idle and for operating said second start means in the event said first finder switch is busy and governed in response to the presence of a calling line in said second group of lines for operating said second start means in the event said second finder switch is idle and for operating said first start means in the event said second finder switch is busy.

17. In a telephone system, first and second groups of lines, first and second finder switches, each of said finder switches comprising a contact bank including first and second groups of contact sets and an associated wiper set having access to the first and second groups of contact sets in the contact bank, the lines in said first group of lines being terminated by the contact sets in the first group of contact sets in the contact bank of said first finder switch and by the contact sets in the second group of contact sets in the contact bank of said second finder switch, the lines in said second group of lines being terminated by the contact sets in the second group of contact sets in the contact bank of said first finder switch and by the contact sets in the first group of contact sets in the contact bank of said second finder switch, the wiper set of each of said finder switches being operative to select a contact set accessible thereto in the associated contact bank terminating a calling line, first blocking means operative to prevent the wiper set of said first finder switch from selecting a contact set in the second group of contact sets in the associated contact bank, second blocking means operative to prevent the wiper set of said second finder switch from selecting a contact set in the second group of contact sets in the associated contact bank, first start means operative to initiate operation of the wiper set of said first finder switch, means for arresting operation of the wiper set of said first finder switch when it selects a contact set in the associated contact bank terminating a calling line, second start means operative to initiate operation of the wiper set of said second finder switch, means for arresting operation of the wiper set of said second finder switch when it selects a contact set in the associated contact bank terminating a calling line, means governed while both the wiper set of said first finder switch and the wiper set of said second finder switch are operating for operating both said first blocking means and said second blocking means, and means governed in response to the presence of a calling line in said first group of lines for operating said first start means in the event said first finder switch is idle and for operating said second start means in the event said first finder switch is busy and governed in response to the presence of a calling line in said second group of lines for operating said second start means in the event said second finder switch is idle and for operating said first start means in the event said second finder switch is busy.

18. In a telephone system, first and second groups of lines, first and second switches, each of said switches having access to each of the lines in each of said groups of lines, first blocking means normally effective positively to prevent said first switch from selecting a line in said second group of lines, second blocking means normally effective positively to prevent said second switch from selecting a line in said first group of lines, means for operating said first switch to select one of said lines accessible thereto, thereby to render busy said first switch, means governed when said first switch is rendered busy for rendering ineffective said second blocking means, means for operating said second switch to select one of said lines accessible thereto, thereby to render busy said second switch, and means governed when said second switch is rendered busy for rendering ineffective said first blocking means.

19. In a telephone system, first and second groups of lines, first and second switches, each of said switches having access to each of the lines in each of said groups of lines, first blocking means operative to prevent said first switch from selecting a line in said second group of lines, second blocking means operative to prevent said second switch from selecting a line in said first group of lines, means for initiating operation of said first switch, thereby to cause said first switch to select a line accessible thereto, means for arresting operations of said first switch when a line is selected thereby, means for initiating operation of said second switch, thereby to cause said second switch to select a line accessible thereto, means for arresting operations of said second switch when a line is selected thereby, and means governed while both said first switch and said second switch are operating for operating both said first blocking means and said second blocking means.

20. In a telephone system, first and second groups of lines, first and second switches, each of said switches having access to each of the lines in each of said groups of lines, first blocking means operative to prevent said first switch from selecting a line in said second group of lines, second blocking means operative to prevent said second switch from selecting a line in said first group of lines, means for initiating operation of said first switch, thereby to cause said first switch to select a line accessible thereto, means for arresting operations of and for rendering busy said first switch when a line is selected thereby, means governed while said first switch is operating and when said second switch is idle for operating said first blocking means, means for initiating operation of said second switch, thereby to cause said second switch to select a line accessible thereto, means for arresting operation of and for rendering busy said second switch when a line is selected thereby, and means governed while said second switch is operating and when said first switch is idle for operating said second blocking means.

21. In a telephone system, first and second groups of lines, first and second switches, each of said switches having access to each of the lines in each of said groups of lines, first blocking means operative to prevent said first switch from selecting a line in said second group of lines, second blocking means operative to prevent said second switch from selecting a line in said first group of lines, means for initiating operation of said first switch, thereby to cause said first switch to select a line accessible thereto, means for arresting operations of and for rendering busy said first switch when a line is selected thereby, means governed while said first switch is operating and when said second switch is idle for operating said first blocking means, means for initiating operation of said second switch, thereby to cause said second switch to select a line accessible thereto, means for arresting operation of and for rendering busy said second switch when a line is selected thereby, means governed while said second switch is operating and when said first switch is idle for operating said second blocking means, and additional means governed while both said first switch and said second switch are operating for operating both said first blocking means and said second blocking means.

22. In a telephone system, first and second groups of lines, first and second groups of

switches, each of the switches in each of said groups of switches having access to each of the lines in each of said groups of lines, first blocking means normally effective positively to prevent the switches in said first group of switches from selecting a line in said second group of lines, second blocking means normally effective positively to prevent the switches in said second group of switches from selecting lines in said first group of lines, means including a first distributor for operating idle ones of the switches in said first group of switches in a predetermined order to select the lines accessible thereto, each of the switches in said first group of switches being rendered busy when it selects a line, means governed when all of the switches in said first group of switches are rendered busy for rendering ineffective said second blocking means, means including a second distributor for operating idle ones of the switches in said second group of switches in a predetermined order to select the lines accessible thereto, each of the switches in said second group of switches being rendered busy when it selects a line, and means governed when all of the switches in said second group of switches are rendered busy for rendering ineffective said first blocking means.

23. In a telephone system, first and second groups of lines, first and second groups of switches, each of the switches in each of said groups of switches having access to each of the lines in each of said groups of lines, first blocking means operative to prevent the switches in said first group of switches from selecting lines in said second group of lines, second blocking means operative to prevent the switches in said second group of switches from selecting lines in said first group of lines, means including a first distributor for assigning idle ones of the switches in said first group of switches in a predetermined order, means for initiating operation of an assigned switch in said first group of switches, thereby to cause said last-mentioned switch to select a line accessible thereto, means for arresting operation of and for rendering busy said last-mentioned switch when a line is selected thereby, means including a second distributor for assigning idle ones of the switches in said second group of switches in a predetermined order, means for initiating operation of an assigned switch in said second group of switches, thereby to cause said last-mentioned switch to select a line accessible thereto, means for arresting operation of and for rendering busy said last-mentioned switch when a line is selected thereby, and means governed while a switch in said first group of switches and a switch in said second group of switches are operating for operating both said first blocking means and said second blocking means.

24. In a telephone system, first and second groups of lines, first and second groups of switches, each of the switches in each of said groups of switches having access to each of the lines in each of said groups of lines, first blocking means operative to prevent the switches in said first group of switches from selecting lines in said second group of lines, second blocking means operative to prevent the switches in said second group of switches from selecting lines in said first group of lines, means including a first distributor for assigning idle ones of the switches in said first group of switches in a predetermined order, means for initiating operation of an assigned switch in said first group of switches,

thereby to cause said last-mentioned switch to select a line accessible thereto, means for arresting operation of and for rendering busy said last-mentioned switch when a line is selected thereby, means governed while a switch in said first group of switches is operating and when there is an idle switch in said second group of switches for operating said first blocking means, means including a second distributor for assigning idle ones of the switches in said second group of switches in a predetermined order, means for initiating operation of an assigned switch in said second group of switches, thereby to cause said last-mentioned switch to select a line accessible thereto, means for arresting operation of and for rendering busy said last-mentioned switch when a line is selected thereby, and means governed while a switch in said second group of switches is operating and when there is an idle switch in said first group of switches for operating said second blocking means.

25. In a telephone system, first and second groups of lines, first and second groups of switches, each of the switches in each of said groups of switches having access to each of the lines in each of said groups of lines, first blocking means operative to prevent the switches in said first group of switches from selecting lines in said second group of lines, second blocking means operative to prevent the switches in said second group of switches from selecting lines in said first group of lines, means including a first

5 distributor for assigning idle ones of the switches in said first group of switches in a predetermined order, means for initiating operation of an assigned switch in said first group of switches, thereby to cause said last-mentioned switch to select a line accessible thereto, means for arresting operation of and for rendering busy said last-mentioned switch when a line is selected thereby, means governed while a switch in said first group of switches is operating and when there is an idle switch in said second group of switches for operating said first blocking means, means including a second distributor for 10 assigning idle ones of the switches in said second group of switches in a predetermined order, means for initiating operation of an assigned switch in said second group of switches, thereby to cause said last-mentioned switch to select a line accessible thereto, means for arresting operation of and for rendering busy said last-mentioned switch when a line is selected thereby, means governed while a switch in said second group of switches is operating and when there is an idle switch in said first group of switches for 15 operating said second blocking means, and additional means governed while a switch in said first group of switches and a switch in said second group of switches are operating for operating both said first blocking means and said second blocking means.

PIER BAKKER.
